US0D1090627S

(12) United States Design Patent (10) Patent No.: US D1,090,627 S
(45) Date of Patent: * Aug. 26, 2025

(54) DISPLAY SCREEN WITH ICON

(71) Applicant: CENTRALSCALE TECHNOLOGIES, LLC, Lake Mary, FL (US)

(72) Inventors: Ye Zhou, Oviedo, FL (US); Ryan Trenholm, Kelowna (CA); Jason Parker, Clarkesville, GA (US); Emily Dalton, Harrisonburg, VA (US)

(73) Assignee: CENTRALSCALE TECHNOLOGIES, LLC, Lake Mary, FL (US)

() Term: 15 Years

(21) Appl. No.: 29/960,322

(22) Filed: Aug. 29, 2024

Related U.S. Application Data

(63) Continuation of application No. 29/868,216, filed on Nov. 25, 2022, now Pat. No. Des. 1,045,928.

(57)

CLAIM

The ornamental design for a display screen with icon, as shown and described.

DESCRIPTION

The FIGURE is a front view of a display screen with an icon, showing our new design.

The broken lines of uneven length show the display screen and form no part of the claimed design.

1 Claim, 1 Drawing Sheet
